CLAIM

The ornamental design for a shoe, as shown and described.

DESCRIPTION

FIG. 1 is a medial side perspective view of an embodiment of a shoe, it being understood that there is no claim being made to the bottom features, other than those visible in the views of the drawing disclosure for this embodiment, therefore the bottom view of this embodiment has been omitted.

FIG. 2 is a lateral side perspective view of the shoe of FIG. 1.

FIG. 3 is a medial side view of the shoe of FIG. 1.

FIG. 4 is a lateral side view of the shoe of FIG. 1; and, FIG. 5 is a rear view of the shoe of FIG. 1.

The remainder of the shoe shown in broken lines in FIGS. 1-5 shows unclaimed subject matter only and forms no part of the claimed design.
